IRONING MACHINE

Cecil E. Clement, Newton, Iowa

Application October 15, 1934, Serial No. 748,280

4 Claims. (Cl. 38—61)

This invention relates to power driven roll-ironers and more particularly to that type of ironer which is conventionally used for domestic ironing.

5 The invention has for its principal object the provision of novel means for adjusting the contact pressure between an ironing shoe and roller.

Another object is to provide means whereby the contact pressure may be quickly and conveniently adjusted during practical use of the ironer.

10 A further object is to combine the adjustment means and safety release means in a single mechanism, whereby operation of the adjustment means or safety release means is accomplished by manipulation of a single handle.

Other objects will appear in the following description and accompanying drawings in which—

Fig. 1 is a rear side elevational view of the ironer to be described;

20 Fig. 2 is a sectional end elevational view of adjustment and release mechanism to be described, taken from line 2—2 in Fig. 1;

Fig. 3 is an enlarged end elevation of the ironer as viewed from the left in Fig. 1, with certain 25 cover portions broken away to permit clear view of underlying parts, and

Fig. 4 is an enlarged detail sectional view showing parts to be described, the same being taken 30 from line 4—4 in Fig. 3.

30 Before proceeding with the description, it may be in order to state that ironing machines of the domestic type are used for ironing garments or materials of great variety, the extremes of which might be represented by a lady's fine handkerchief, ironed flat, and a heavy woolen blanket, ironed folded. Obviously, a great variation in thickness is here represented.

In the case of a flat handkerchief, the ironing 40 shoe will rest in a position quite close to the roll, whereas with a heavy folded blanket, the shoe will occupy a position a substantial distance from the roll.

Considering this, it will be apparent that since 45 the roll is usually mounted upon fixed bearings, the shoe must be so mounted that ironing pressure may be exerted in a yielding manner in order to accommodate materials of varying thickness.

50 In order to accomplish this yielding pressure, the structure of conventional ironing machines is so arranged that spring coupling means is inserted in the shoe operating mechanism in such a manner that while the shoe operating mechanism itself may be operated in a rigid manner,

connection between the mechanism and shoe may be such that the shoe has a yielding relationship to the roll.

Practical considerations require that the spring coupling means have substantial strength in order that suitable contact pressure may be maintained as between the ironing roll and shoe.

It will be apparent that if the spring coupling means be so adjusted that suitable ironing pressure is applied to the shoe when the shoe occupies a position in close proximity to the roll, as in the case of a handkerchief, insertion of a heavy folded blanket will cause the shoe to occupy a position a considerable distance from the roll, therefore the spring coupling means must, for example, be more highly compressed, which compression would react upon the shoe in such a manner that the pressure exerted upon the blanket may be sufficiently excessive to make proper ironing or operation of the ironing mechanism difficult.

It is an object of this invention to provide manual means, inserted between the spring coupling means above noted and the ironing shoe whereby the operator of an ironing machine may adjust the pressure of the shoe, cooperatively with the spring coupling means, to accomplish satisfactory ironing pressure in accordance with requirements of thickness, quality or other considerations.

Proceeding with the description, Fig. 1 discloses an ironing machine unit having a housing 10 by means of which a motor 11 and an ironing roller 12 is supported upon a suitable base 13.

A tubular shaft 14, to be referred to later, is 35 supported at one end by a bearing formed in the housing 10 and at the opposite end by an outboard bearing support 15 secured to base 13.

Near the support 15 is an arm member 16 and a lever member 17. Arm 16 is secured to shaft 14. 40

Lever 17 is rotatably mounted upon shaft 14 and, as best shown in Fig. 2, has a portion 18 extending upwardly and inwardly toward roller 12 carrying a lever structure including a pin 19 upon which is rotatably mounted a cam member 45 20, to be referred to later, and the supporting bracket 12' of an ironing shoe 12". By means of its support upon pin 19, shoe 12" is adapted to contact with ironing roll 12 as indicated in Fig. 2.

Lever 17 also carries a pin 21 upon which is pivotally supported a cradle member 22.

An angularly extending portion 23 of cradle member 22 supports a coil spring 24, the opposite end of which is confined by the head of a 55

bolt member 25. The body of bolt 25 passes through the portion 23 in slideable relation thereto and also through the back web portion of lever 17 to terminate in a threaded portion by means of which a nut 26 is secured to abut the bolt against the thrust action of spring 24.

It will be apparent that spring 24, mounted as shown, tends to hold lever 17 in predetermined position in tensioned relation to arm 16, and 10 that cam 28 is operable, when abutting pin 27, which is secured in arm 16, to force arms 16 and 17 apart, thus holding spring 24 in somewhat compressed position.

Cam 28, as here illustrated, has two indents 28 15 and 29, each indent occupying different positions relative to the center of pin 19.

Cam 28 is included in a lever structure which also includes a manually operable arm 30 by means of which the cam 28 may be rotated upon 20 pin 19 to position either of indents 28 or 29 in register with pin 27 of lever 17, to adjust the position of arm 16 relative to lever 17, which movement is induced by spring 24 as already noted.

25 Considering for the moment that arm 16 is stationary, it will be apparent that with arm 30 positioned as indicated in dotted lines in Fig. 2, indent 28 will be in register with pin 27 whereby by pressure of predetermined extent will be set 30 up as between arm 16 and ironing roll 12 through the ironing shoe 12", whereas with arm 30 moved to the position shown in solid lines in Fig. 2, indent 28, which is somewhat closer to pin 19, will allow arm 16 to move toward roll 12 (this movement being brought about by spring 35) thus allowing spring 24 to relax somewhat whereby by pressure of the shoe upon the roll is reduced.

Obviously continued backward movement of 40 arm 30 will rotate cam 28 to a position where the cam is entirely out of contact with pin 27, in which case spring 24 may operate to rotate lever 17 backwardly upon shaft 14, toward arm 16, to withdraw shoe 12" away from roll 12.

Referring to Fig. 3, it will be noted that within 45 housing 18, the shaft 14 carries an affixed arm 31 to which is pivotally connected a cradle member 32.

Extending within the lower end of cradle 32 is 50 a bolt extension 33 of an eccentric band member 34.

Between the head of bolt 33 and connecting portion of cradle 32 is a compression spring 35, best shown in Fig. 4.

Fig. 3 indicates an eccentric band member 34 55 rotatably mounted upon an eccentric member 36.

Means for rotating eccentric 36 is provided by motor 11 through worm 37 acting upon a worm gear 38 which rotates upon the same axial center as eccentric 36.

60 The eccentric rotating mechanism, not being a part of this invention, will not be described further than to say that suitable clutching mechanism is disposed between worm gear 38 and eccentric 36, whereby the eccentric may be rotated 65 to the position shown in Fig. 3 to rotate arm 31, shaft 14 and arm 16, together with the shoe mechanism above described to place shoe 12" in contact with roll 12.

Subsequent operation of the eccentric would 70 result in rotation thereof to a position diametrically opposite the position shown, whereby the described shoe mechanism would be operated to withdraw shoe 12" away from the ironing roll. A third operation of the eccentric would place it 75 again in original position, as in Fig. 3. Thus, in-

intermittent rotation of the eccentric results in alternately placing the ironing shoe in contact with the ironing roll and withdrawing it therefrom.

The relative adjustment of the mechanism described is such that when the eccentric is placed as shown in Fig. 3, with shoe 12" in contact with roll 12, the length of stroke of the eccentric is somewhat more than is necessary to place shoe 12" in contact with roll 12. Thus, when the 10 parts are placed as shown, the shoe is brought into contact with the roll before the eccentric has completed its stroke, with the result that when the movement of the arm mechanism is arrested by the shoe's coming into contact with 15 the roll, continued movement of the eccentric withdraws the bolt extension 33 from the cradle 32 to compress spring 35. Spring 35 and associated parts thus become a means whereby shoe 12" is resiliently held in pressure contact with 20 the ironing roller.

The effect of placing materials of variable thickness between the ironing shoe and roll has already been noted. Obviously, with spring 35 shown in Fig. 3, with sufficient pressure to properly iron thin materials, the introduction of comparatively thick material therebetween would result in comparatively extensive compression of spring 35 with consequent excessive 30 pressure upon the shoe.

In practical use, for ironing comparatively thin materials, the hand arm 30 would be placed as shown in dotted lines in Fig. 2, with indent 29 in engagement with pin 27, thus giving maximum 35 pressure between shoe 12" and roll 12, when the same are in close proximity, whereas when thick materials are to be ironed, lever 30 may be moved to the position shown in solid lines with indent 28 in engagement with pin 27 to permit the shoe to occupy a position more or less distant from the shoe without excessively compressing spring 35. Obviously, any number of indents may be provided to bring about graduated adjustment.

Hand arm 30 is also available to remove the 45 shoe from the roll by continued backward movement as already described.

What I claim is:

1. In an ironing machine of the class described, the combination of an ironing roll, a shoe cooperatively supported therewith, mechanism for moving the shoe into contact with the roll including pressure means for resiliently holding the shoe in pressure relation with the roll, and a manually operable cam mechanism intermediate the pressure means and shoe for adjusting the pressure of the shoe upon the roll without removing all pressure.

2. In a power driven ironing machine, the combination of an ironing roll, an ironing shoe, 60 mechanism for revolving the ironing roll and actuating the shoe into and out of pressure contact with the roll, a spring interposed in the shoe actuating mechanism to make the contact between the shoe and roll resilient, and a manually operable cam interposed in the shoe actuating mechanism to adjust and relieve the pressure between the roll and shoe.

3. In a power driven ironing machine, the combination of an ironing roll, an ironing shoe, mechanism for revolving the ironing roll and actuating pressure contact between the shoe and the roll, a spring interposed in the shoe actuating mechanism to make the contact between the shoe and roll resilient, and a manually operable 70 mechanism to adjust and relieve the pressure between the roll and shoe.

cam interposed in the shoe actuating mechanism to adjust and relieve the pressure between the roll and shoe.

4. In a power driven ironing machine, the combination of an ironing roll, an ironing shoe, mechanism for revolving the ironing roll and actuating pressure contact between the shoe and the roll, a spring interposed in the shoe actua-

ting mechanism to make the contact between the shoe and roll resilient, and a manually operable cam with multiple stages interposed in the shoe actuating mechanism to adjust and relieve the pressure between the roll and shoe for variable thicknesses of garments or to relieve all pressure. 5
